UNITED STATES PATENT OFFICE.

JOSEPH H. CHAMP, OF CLEVELAND, OHIO, ASSIGNOR TO THE BISHOP & BABCOCK COMPANY, OF SAME PLACE.

APPARATUS FOR DISPENSING LIQUIDS.

SPECIFICATION forming part of Letters Patent No. 650,351, dated May 22, 1900

Application filed December 18, 1899. Serial No. 740,644. (No model.)

To all whom it may concern:

Be it known that I, JOSEPH H. CHAMP, a citizen of the United States, and a resident of Cleveland, county of Cuyahoga, and State of Ohio, have invented a new and useful Improvement in Apparatus for Dispensing Liquids, of which the following is a specification, the principle of the invention being herein explained and the best mode in which I have contemplated applying that principle so as to distinguish it from other inventions.

The object of the invention is to provide improved means for dispensing liquids.

The invention consists of the means hereinafter described and finally pointed out in the claims.

The annexed drawings and the following description set forth in detail certain mechanism embodying the invention, such disclosed means constituting but one of various mechanical forms in which the principle of the invention may be used.

Figure I is a side elevation of my liquid-dispensing apparatus as it may be applied in use in connection with a cooling-chamber and a primary vessel containing aerated liquid. Fig. II is a vertical central section of my liquid-dispensing apparatus, the apparatus being shown in position such as obtains when liquid flows into the dispensing-chamber. Fig. III is a sectional plan view taken on the broken line 3 3 of Fig. II. Fig. IV is a central vertical section of the dispensing apparatus, taken in a plane at right angles to that in which Fig. II is taken. Fig. V is a sectional plan on line 5 5 of Fig. IV. Fig. VI is a sectional plan on line 6 6 of Fig. IV.

A represents a primary vessel for containing aerated liquid. It is connected by pipe B with coil C, such coil being located in cooling-chamber D. My dispensing apparatus may be attached to the face of such cooling-chamber and have its nozzle E coupled to said coil C. Said nozzle has a central duct a, which is in constant open communication with the interior of said cooling-coil C, such duct extending forward and being adapted to have registering communication with way b, formed in rotary valve F. This rotary valve F is further provided with way c, adapted to have registering communication

with duct d, formed in the valve-seat G, and having constant communication with the upper portion of dispensing-chamber H. Said way b of the rotary valve has constant communication with duct e, formed in the central vertical line of said valve and of said valve-seat and of said dispensing-chamber, the lower portion of such duct e having constant communication with the lower portion of said dispensing-chamber. Said way c of said rotary valve has constant communication with the valve-chamber J, within which said rotary valve is located. Such valve-chamber has constant communication with duct f, whose opposite extremity has free communication with the cooling-chamber D. A cap K is screwed into the top of valve-chamber J. A spiral spring L is compressed between the upper portions of said rotary valve and said cap and tends to maintain said rotary valve against accidental displacement.

Extending through duct e is valve-stem M, whose lower end is connected to valve N, such valve controlling the discharge of liquid from the bottom of dispensing-chamber H. A spiral spring g encircles the lower portion of such valve-stem and is compressed between the top of valve N and the bottom of sleeve h, which latter constitutes the wall of duct e within the dispensing-chamber. The upper portion of said valve-stem is loosely connected to lever-handle P. Such handle is pivotally fulcrumed to tubular stem Q of the rotary valve, a spring j tending to maintain such handle in horizontal position, as shown in Fig. II, the formation and connection of the parts being such that the rotary valve may be rotated on its seat by the lever-handle operating upon the valve-stem Q without having effect to either raise or lower valve-stem M of the outlet-valve N. In like manner the lever-handle may operate in connection with said discharge-valve stem M without affecting the position of the rotary valve.

When liquid is to be drawn from the primary containing-chamber A into the dispensing-chamber H, the apparatus is in the position shown in Fig. II. The aerated liquid thereby passes through duct a into way b of the rotary valve and thence to duct e into the lower portion of the dispensing-chamber.

When sufficient liquid has thus been let into the dispensing-chamber, the operator rotates the rotary valve by turning the lever-handle horizontally through a quarter of a circle's revolution, whereupon duct *b* of the rotary valve is placed out of registering communication with duct *a*, and duct *c* of the rotary valve is placed in registering communication with duct *d* of the rotary valve-seat. Thereby the gas within the dispensing-chamber is permitted to escape by duct *d*, way *c*, valve-chamber *J*, and duct *f* into the cooling-chamber *D*. When the liquid within the dispensing-chamber is sufficiently relieved from pressure, the operator presses the lever-handle down and the parts assume position shown in Fig. IV. The liquid without undue pressure is thus permitted to pass into a glass for the consumer. When the desired quantity of liquid is thus drawn at the will of the operator from the dispensing-chamber, then the operator permits the springs *g* and *j* to close the valve *N* and restore the lever-handle into the horizontal position, all as shown in Fig. II.

25 Other modes of applying the principle of my invention may be employed instead of the one explained, change being made as regards the mechanism herein disclosed, provided the means covered by any one of the following 30 claims be employed.

I therefore particularly point out and distinctly claim as my invention—

1. The combination of a dispensing-chamber having a liquid-inlet and a liquid-outlet, 35 valves severally governing such inlet and outlet, a handle connected by intermediate means jointly to said two valves and operating each of the latter independently of the other, substantially as set forth.

40 2. The combination of a dispensing-chamber having a gas-outlet and a liquid-outlet, valves severally governing such two outlets, a handle connected by intermediate means jointly to said two valves and operating each 45 of the latter independently of the other, substantially as set forth.

3. The combination of a dispensing-chamber having a liquid-inlet and a gas-outlet and a liquid-outlet, a valve jointly governing said 50 liquid-inlet and gas-outlet, a valve governing said liquid-outlet, a handle connected by intermediate means jointly to said two valves and operating each of the latter independently of the other, substantially as set forth.

55 4. The combination of a dispensing-chamber having a liquid-inlet and a liquid-outlet, independent valves respectively controlling such inlet and such outlet, each of said valves having a valve-stem exclusive of the other, a handle connected jointly to said two valve-stems and operating each of the latter independently of the other, substantially as set forth.

60 5. The combination of a dispensing-chamber having a liquid-inlet and a liquid-outlet, valves respectively controlling such inlet and such outlet, the stem of one of said valves

being tubular and having the stem of the other valve passing therethrough, a handle connected jointly to said two valve-stems and 70 operating each of the latter independently of the other, substantially as set forth.

6. The combination of a dispensing-chamber having a liquid-inlet and a liquid-outlet, 75 a valve for said inlet, a valve for said outlet, a spring tending to maintain said outlet-valve closed, said inlet-valve having a tubular stem projecting upwardly therefrom, said outlet-valve having a stem projecting upwardly therefrom and passing freely through 80 said inlet-valve tubular stem, a handle connected to the upper extremities jointly of said two valve-stems and adapted to operate each of the latter independently of the other, substantially as set forth.

7. The combination of a dispensing-chamber having a liquid-inlet and a liquid-outlet, a rotary valve controlling said inlet, a rectilinearly-working valve controlling said outlet, a handle connected jointly to the stems 90 of said valves and operating each independently of the other, substantially as set forth.

8. The combination of a dispensing-chamber having a liquid-inlet and a liquid-outlet, 95 a rotary valve controlling said inlet and having a tubular stem, a rectilinearly-working valve controlling said outlet and having a stem passing freely through said tubular valve-stem, a lever-handle fulcrumed on said tubular stem and having its weight-arm connected to the stem of said outlet-valve, substantially as set forth.

9. The combination of a dispensing-chamber having a liquid-inlet and a liquid-outlet and a gas-outlet, a rotary valve having two independent ways and working in a chamber having constant communication with a gas-exhaust duct, a seat for said rotary valve having a liquid-way and a gasway, such rotary valve adapted when in a certain position to establish communication between a liquid-supply duct and said inlet of the dispensing-chamber, and also adapted when in certain other position to establish communication between said gas-outlet of the dispensing-chamber and said rotary-valve chamber, together with a rectilinearly-working valve governing said liquid-outlet of the dispensing-chamber, a spring tending to maintain said outlet-valve closed, a handle connected jointly to respective valve-stems of said inlet and outlet valves and adapted to operate each of the latter independently of the other, substantially as set forth.

10. The combination of a dispensing-chamber having a liquid-inlet and a liquid-outlet, a valve controlling such outlet and having a stem passing freely through said inlet, a handle connected to the projecting extremity of said stem, substantially as set forth.

11. The combination of a dispensing-chamber having a liquid-inlet and a liquid-outlet, a valve controlling such outlet, a spring having its opposite extremities respectively bearing

ing against said valve and the wall of said inlet, said valve having a stem passing freely through said inlet and provided at its projecting end with a handle, substantially as set forth.

12. The combination of a dispensing-chamber having a liquid-inlet and a liquid-outlet, a valve controlling such outlet, a tubular spring having its opposite extremities bearing respectively against said valve and the wall of said inlet, a valve-stem passing loosely through said spring and inlet and having its projecting end provided with a handle, substantially as set forth.

13. The combination of a dispensing-chamber having a liquid-inlet and a liquid-outlet,

a rectilinearly-working valve governing such outlet, a spring tending to maintain said valve closed, a rotary valve having a tubular stem, the stem of said outlet-valve passing freely 20 through said spring and inlet and rotary valve and tubular stem, a handle connected jointly to the upper extremities of said two valve-stems and operating each of the latter independently of the other, substantially as set 25 forth.

Signed by me this 15th day of December, 1899.

JOSEPH H. CHAMP.
